SUBSTITUTED FOR TORN COPY.

UNITED STATES PATENT OFFICE.

DWIGHT ALLEN, OF LEMARS, IOWA, ASSIGNOR TO THE THAT MANUFACTURING COMPANY, OF SAME PLACE.

SOFT SOAP.

SPECIFICATION forming part of Letters Patent No. 501,036, dated July 4, 1893.

Application filed September 23, 1892. Serial No. 446,694. (No specimens.)

To all whom it may concern:

Be it known that I, DWIGHT ALLEN, a citizen of the United States of America, residing at Lemars, in the county of Plymouth and State 5 of Iowa, have invented a new and useful Soft Soap, of which the following is a specification.

My object is to provide a soap specially adapted and always ready to be advantageously used for washing clothing and textile 10 fabrics of every kind, cleaning house, cleaning and polishing painted and varnished furniture, carriages, &c., and also for removing grease and tar from a person's hands and for washing and bathing children and for general 15 use in a family for cleansing purposes.

My invention and composition consists of the following ingredients combined approximately in proportions as follows:—eight (8) pounds of white hard soap, comminuted or 20 chipped, eight (8) pounds of carbonate of soda (sal-soda), two (2) ounces of pulverized borax, thirty (30) grains of chlorate of soda, one (1) dram of concentrated lye, twelve (12) gallons of water. All the ingredients are mixed and

boiled in the water and when cool it will be a 25 white translucent soft soap ready to place in wooden buckets or other suitable vessels adapted for placing the soap upon the market as an article of merchandise that can be readily handled and used as required for the 30 various purposes for which it is adapted.

I am aware that all the ingredients of my composition have heretofore been used in making soap but not in the manner and proportions that I have combined them to produce 35 a soft white soap adapted for toilet use and the various other purposes mentioned.

What I claim, and desire to secure by Letters Patent of the United States, is—

The herein described composition of matter 40 adapted to be used as a soft soap, consisting of hard soap, carbonate of soda, borax, chlorate of soda, concentrated lye and water, in about the proportions specified.

DWIGHT ALLEN.
